US00D904889S

(12) **United States Design Patent** (10) Patent No.: **US D904,889 S**
(45) Date of Patent: **** Dec. 15, 2020**

(54) **CONTAINER**

(71) Applicant: **PepsiCo, Inc.**, Purchase, NY (US)

(72) Inventors: **Advait Bhat**, White Plains, NY (US); **Girish Nilkanth Deshpande**, Carmel, NY (US); **Maximiliano Rodriguez**, Bridgewater, NJ (US); **Benjamin Joseph Tantanella**, New York, NY (US); **Bruno Telesca**, Sandy Hook, CT (US); **Nathan Daniel Grubbs**, West Chester, OH (US); **Ryan Alan Klenke**, St. Henry, OH (US)

(73) Assignee: **PepsiCo, Inc.**, Purchase, NY (US)

(**) Term: **15 Years**

(21) Appl. No.: **29/697,241**

(22) Filed: **Jul. 5, 2019**

(51) LOC (12) Cl. **09-01**

(52) U.S. Cl.

USPC **D9/529**

CLAIM

The ornamental design for a container, as shown and described.

DESCRIPTION

FIG. 1 is a top perspective view of a container showing the claimed design;

FIG. 2 is another top perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

(Continued)

The broken lines in the figures show portions of the container that form no part of the claimed design.

1 Claim, 6 Drawing Sheets
